UNITED STATES PATENT OFFICE.

GEORGE W. MUDD, OF SPRINGFIELD, ILLINOIS.

TRACK-SANDING DEVICE.

SPECIFICATION forming part of Letters Patent No. 630,550, dated August 8, 1899.

Application filed August 18, 1898. Serial No. 688,907. (No model.)

To all whom it may concern:

Be it known that I, GEORGE W. MUDD, a citizen of the United States, residing at Springfield, Illinois, have invented certain new and useful improvements in Track-Sanding Devices, of which the following is a specification.

The object of my invention is to make a track-sanding device that is intended ordinarily to be operated by the excess air-pressure used on locomotives and that can be operated independent of and in conjunction with the slide-valve mechanism which has long been used in track-sanding devices; and my invention consists in the features, combinations, and details of construction hereinafter described and claimed.

In the accompanying drawings, Figure 1 is a plan view of a sand-box, taken in line 1 of Fig. 2, empty of sand and with the slide mechanism removed; Fig. 2, a sectional elevation taken in line 2 of Fig. 1 looking in the direction of the arrow; and Fig. 3, a longitudinal section of a detail, taken in line 3 of Fig. 1 looking in the direction of the arrow.

In making my improved track-sanding device I employ the usual sand-box A, provided with the usual pipes a for carrying the sand from the box to the track. In the usual construction the upper openings to these pipes, by which the sand in the box is permitted to flow through the pipes, are closed by slide-valves which are under the control of the engineer, so that by mechanical means he can open or close them, as desired. While I have shown these pipes and openings in Figs. 1 and 2, I have not considered it necessary to show the slide-valves or mechanism for operating them, as the same are well known and are not intended to be modified or changed in their construction or operation in my improved track-sanding device. They may be used just as has been done for many years.

In order, however, to impart to the device a dual capacity, as it were, so that it may be used either in the old way or by the excess air-pressure on the locomotive, I lead a pipe B from the air-reservoir to the sand-box, which it enters. The pipe is carried across from one side of the box to the other, being bent or curved upward, as at b, to properly pass over the pyramidal elevation C in the

center of the box. It is provided with two branches D and D', which lead, respectively, to holes d and d', intersecting the original sand-pipes a at a desired distance below their upper openings. These branch pipes are provided at their tops, in their horizontal portions, with holes e and e', preferably one in each branch, so that the sand when the box is filled enters the pipes by gravity. Inasmuch, however, as the branch pipes are curved or bent up near their exit ends, as at d', to form return-bends which bar or obstruct the passage of sand therethrough and also to give the proper vertical direction to the ends of the pipes in making the connection with the original sand-pipes a, the sand entering the horizontal portion through the holes e and e' cannot flow out or escape until desired. Nor can the sand escape or flow out through the original pipes a, as such pipes will be closed by the slide-valves, as will be understood from the explanations above given. In order to secure the proper effect of the air and give it power to force out the sand when admitted through the pipe B, I arrange a gradually-contracting nipple or nozzle E in each of the branch pipes intermediate the point where the air enters and the sand-holes e and e', so that the air passes through such nozzle and is concentrated or contracted in volume before reaching the point where the sand enters the pipes. This will be clearly understood from an inspection of Fig. 3 of the drawings, where the arrangement is shown in detail.

Whenever it is desired to apply sand to the track, the engineer admits air under pressure from the reservoir to the pipe B. This air passes along the pipe until it reaches the branch pipe D within the sand-box. A portion of the entering air passes through the nozzle and along such branch, while the remainder follows the pipe across the sand-box and enters the branch D', where it passes through a similar nozzle as it enters such branch. The air thus entering the branch pipes in a jet or contracted stream or current is of sufficient force to move the sand ahead of it along the branch pipes, with the new sand constantly entering, and force it into and out through the original sand-pipes a. If, however, for any reason the air-pressure in the reservoir be insufficient, or if the air

pumping and compressing mechanism be out of order, or if the air be interrupted, so that air under pressure is not obtainable, the engineer is still able to apply sand to the track 5 by operating the original slide-valve mechanism, which is controllable at will by mechanical means. It is thus possible to combine in the same track-sanding apparatus means for applying the sand either mechanically or through air-pressure, either separately or together and simultaneously, so as to insure the presence of means at all times to apply sand to the track, which is not the case where means only are provided for applying the sand mechanically or by air-pressure, as in the one case the sand-pipes may become clogged up or in the other the air give out, become insufficient, or not be applicable. At the same time it is possible to apply my air-pressure mechanism to the original track-sanding devices in use without material expense or trouble either for the additional means or for changes in the original devices in order to apply them, because, as 20 will be seen, all that is necessary is to control or provide the device with the holes d and d' , intersecting the original sand-pipes, and insert my additional appliance.

What I regard as new, and desire to secure 30 by Letters Patent, is—

1. In a track-sanding apparatus, the combination of a sand-box provided with two discharge-ducts extending out therefrom and substantially opposite each other, a supply- 35 pipe connected with a source of compressed

air and extending diametrically across the box at or near its bottom portion, a branch pipe extending from each end of the diametrical supply-pipe inside of the box and connecting such supply-pipe with the discharge- 40 ducts, an upward return-bend on the end of each branch pipe where they connect with the discharge-ducts to provide bars to the discharge of sand, and a perforation in each branch pipe intermediate the supply-pipe and the return-bend, substantially as described.

2. In a track-sanding apparatus, the combination of a sand-box provided with two discharge-ducts extending out therefrom and substantially opposite each other, a supply- 45 pipe connected with a source of compressed air and extending across the box at or near its bottom portion, a branch pipe extending laterally from each end of the supply-pipe inside of the box and connecting such supply- 50 pipe with the discharge-ducts, an upward return-bend on the end of each branch pipe where they connect with the discharge-ducts to provide bars to the discharge of sand, a perforation in each branch pipe on the upper 55 side thereof intermediate the supply-pipe and the return-bend, and an injector-nozzle arranged in each branch pipe intermediate the supply pipe and the perforation, substantially as described.
